CLAIM

The ornamental design for the dusting device, as shown and
described.

DESCRIPTION

FIG. 1 is a side perspective view of a dusting device showing
our new design;
FIG. 2 is a side view of the dusting device of FIG. 1;
FIG. 3 is a top view of the dusting device of FIG. 1; and,
FIG. 4 is a bottom view of the dusting device of FIG. 1.
The broken lines in the drawings illustrating environmental
structure that form no part of the claimed design.

1 Claim, 3 Drawing Sheets
